UNITED STATES PATENT OFFICE.

MEYER HALPERN, OF NEW YORK, N. Y.

DESIGN FOR A TOOTHBRUSH HOLDER.

Application filed January 20, 1922. Serial No. 288. Term of patent 3½ years.

To all whom it may concern:

Be it known that I, MEYER HALPERN, a citizen of the United States, and a resident of the city, county, and State of New York, have invented a certain new, original, and ornamental Design for Toothbrush Holder, of which the following is a specification, reference being had to the accompanying drawing, forming part thereof.

In the drawing:

I claim:

The ornamental design for toothbrush holder, as shown.

MEYER HALPERN.
